UNITED STATES PATENT OFFICE.

EUGENE HERMITE AND CHARLES F. COOPER, OF POWNALL ROAD, DALSTON, COUNTY OF MIDDLESEX, ENGLAND, ASSIGNEES OF ONE-THIRD TO EDWARD JAMES PATERSON, OF SAME PLACE.

APPARATUS FOR BLEACHING BY ELECTROLYSIS.

SPECIFICATION forming part of Letters Patent No. 378,681, dated February 28, 1888.

Application filed October 25, 1887. Serial No. 253,354. (No model.) Patented in England February 8, 1887, No. 1,993.

To all whom it may concern:

Be it known that we, EUGENE HERMITE, a citizen of the United States, and CHARLES FRIEND COOPER, a citizen of England, both 5 residing at Pownall Road, Dalston, in the county of Middlesex, England, have invented a new and useful Improvement in Apparatus for Electrolyzing, Bleaching, or Disinfecting Liquor, of which the following is a specification.

Our invention relates to apparatus for electrolyzing in a continuous manner solutions, usually those of chlorides, employed for bleaching or disinfecting purposes, the solutions being caused to circulate through the vessel or vessels in which they act, then through the electrolyzing apparatus, where they are subjected to the action of a current of electricity, then back to the vessel or vessels to act again, 20 and so on continuously.

Figure 1 of the accompanying drawings is a longitudinal section. Fig. 2 is a transverse section, and Fig. 3 is a plan, of electrolyzing apparatus according to our invention.

25 Within a trough, A, having an inlet, a, and outlet a' for the liquor to be electrolyzed, we fix on insulating-supports several hollow cylinders, B, of which three are shown in the drawings, each of these cylinders being a shell 30 of platinum or metal lined or internally plated with platinum. Centrally within each of these cylinders a plunger, C, of zinc, is made to reciprocate to and fro, all these plungers being for that purpose attached to a cross-head, D, 35 from which a rod, E, passing through a stuffing-box, is linked by a connecting-rod, F, to a revolving crank, G. Each plunger C passes through guides H, armed with scrapers h, the edges of which lightly bear on the surface of 40 the zinc.

The cylinders B are connected by a conducting-wire, W, to one terminal of an electric generator, from the other terminal of which a wire, W', leads to a set of brushes, K, that rub 45 on the rods E, so as to communicate electrically with the zinc plungers C. The liquor entering by a, flowing along the trough A to a', through the narrow annular spaces between

the cylinders B and the plungers C, while the current of electricity passes through it, becomes electrolyzed, and the plungers C as they move to and fro have their surfaces kept clean by the scrapers h.

Although in what precedes we have mentioned platinum or platinized surfaces as being 50 suitable for the one electrode or set of electrodes in the apparatus, there are cases in which material cheaper than platinum can be employed, especially when it has only to transmit a moderate current of electricity. In 55 such cases we use pure plumbago, either natural plumbago cut to the desired form or plumbago compressed to the form required, or glass, ceramic ware, vulcanite, or other inert non-conducting material faced with plumbago. 65

When plumbago is used for forming the conducting-facing, it should be carefully purified by boiling it in hydrochloric acid while chloride of potash is added in several doses to the 70 boiling mixture.

Having thus described the nature of our invention and the best means we know of carrying it out in practice, we claim—

In apparatus for electrolyzing, bleaching, or disinfecting liquor, the combination of a set 75 of horizontal cylinders, of platinum or its equivalent, fixed insulated in a trough through which the liquor flows, with zinc plungers moving to and fro within the said cylinders and through guides armed with scrapers, substantially as described.

In testimony whereof we have signed our names to this specification, in the presence of two subscribing witnesses, this 10th day of October, A. D. 1887.

E. HERMITE.
CHARLES F. COOPER.
